UNITED STATES PATENT OFFICE.

MALCOLM MOLLAN, OF BROOKLYN, NEW YORK.

AUTOMATIC STOP FOR GRAPHOPHONES.

1,378,603.

Specification of Letters Patent. Patented May 17, 1921.

Application filed March 30, 1920. Serial No. 369,907.

To all whom it may concern:

Be it known that I, MALCOLM MOLLAN, a citizen of the United States, and resident of Brooklyn, in the county of Kings and 5 State of New York, have invented certain new and useful Improvements in Automatic Stops for Graphophones, of which the following is a specification.

This invention relates to certain new and 10 useful improvements in automatic stops for graphophones, and has particular reference to a device adapted to be mounted on the frame of the graphophone in position to be engaged by the tone arm for setting the 15 brake.

A further object of the invention is to provide an adjustable automatic stop device for graphophones whereby record disks of different diameters may be used, with the 20 stop device adjusted for operation at the desired point adjacent the axis of the disk, the said device also including mechanism to permit a fine adjustment so that records varying in lengths of spiral grooves, as one 25 or two spirals may be accommodated.

With the above objects in view and others that will appear as the nature of the invention is better understood, the same consists in the novel construction, combination and 30 arrangement of parts to be hereinafter more fully described and then claimed.

In the accompanying drawing forming a part of this application, and to which reference is had by like numerals indicating corresponding parts throughout the several 35 views,

Figure 1 is a fragmentary top plan view of a portion of a graphophone with the present invention operatively positioned 40 thereon, and broken away,

Fig. 2 is a front elevational view of the stop device, the dotted line position showing the same adjusted for a smaller second disk,

Fig. 3 is an end elevational view of the same, and

Fig. 4 is a horizontal sectional view through the plunger cylinder.

The invention briefly described embodies 50 a mounting plate to which a horizontal cylinder is attached, and within which cylinder a plunger rod is adapted to be shifted for engagement with the stop lever of the graphophone. An adjustable vertical stand 55 ard is carried by the mounting plate and supports a swinging rod that is adapted to

be moved by the graphophone tone arm, which movement is communicated to the plunger for setting the brake. The vertical standard being adjustably pivotally supported at its lower end, is adapted to be moved to different positions to cause the operation of the plunger at different points.

Referring more in detail to the accompanying drawing, and particularly to Fig. 65 1, there is illustrated a conventional form of graphophone including the frame 5 having the disk turn-table 6 rotatably mounted thereon with the tone arm 7 (shown in dotted lines) moving over the turn-table. 70 A stop is provided for the turn-table and embodies a lever 8 pivoted as at 9 beneath the turn-table 6 and having a spring 10 for holding the lever 8 at either side of its 75 center of throw.

The present invention shown in detail in Figs. 2, 3, and 4, includes an angle mounting plate, the base 11 of which is secured to the frame 5 of the graphophone at a point adjacent the stop lever 8, the leg 12 80 extending perpendicularly therefrom. A horizontal cylinder 13 is suitably secured to the inner face of the leg 12 while the inner end thereof is provided with crossed diametrical slots 14 and 15 that extend inwardly from said end. A spring 16 is secured exteriorly of the cylinder 13 and overlies one side of the slot 14, and is provided with a substantially S-shaped extension 17 85 projecting over the slotted end of the cylinder, the spring extension controlling access to the slots 14 and 15. As clearly shown in Fig. 4, a plunger rod 18 works in the cylinder 13 and is provided upon the inner end thereof with a ball 19 positioned 90 inwardly of the S-shaped spring extension 17, for purposes presently to appear. The outer end of the plunger 18 is provided with a head 19a that is shouldered as indicated in said figure to limit the inward 100 movement thereof.

A vertical standard or post 20 having a flat bearing face 21 at its lower end is supported upon the horizontal screw 22 extending through the vertical leg 12 of the 105 mounting base plate 11, the screw 22 holding the post 20 in vertical or adjusted angular positions. A hook 23 is carried by the post 20 at a point adjacent the upper end thereof and is adapted to receive the upper 110 eye end 24 of the rod 25, the lower end of said rod extending downwardly through

the vertical slot 15 in the cylinder 13, as shown in Figs. 2 and 4 and positioned inwardly of the S-shaped spring extension 17 for engagement with the ball end 19 of 5 the plunger rod 18.

With the device constructed as above described, and attached to the upper frame 5 of a graphophone, the tone arm 7 of the graphophone having the sound box thereof 10 moving over a record is adapted to engage the rod 25 to shift the lower end thereof in the vertical slot 15 of the cylinder 13 for engagement with the plunger rod 18. The head of the plunger normally contacting 15 the stop lever 8 when the lever is in its open position, immediately starts to shift the lever when projected from the cylinder by the movement of the rod 25 until the lever 8 is moved upon its pivot 9 to shift 20 the spring to the opposite side of the center thereof, at which time the lever, under influence of the spring 10 will complete its movement and apply the brake to the turn-table 6. In order to accommodate the device 25 for playing record disks of different diameters, and where the spiral grooves extend to a position nearer the axis of the turn-table 6, the vertical post 20 may be moved upon its screw bearing 22 to the 30 dotted line position shown in Fig. 2 so that it will be necessary for the tone arm 7 to move a greater distance toward the center of the turn-table to operate the rod 25 and the plunger 18.

To compensate for a fine adjustment of the coöperating parts and to limit a useless throw of the plunger rod 18, there is provided a screw 26 carried by the post 20 and adapted to be adjusted by limiting the 40 swinging movement of the rod 25 and with the consequent control of the plunger rod 18.

What is claimed as new is:

1. An automatic stop device for graphophones comprising in combination with the 45 graphophone tone arm and brake lever, a mounting base fixed to the graphophone frame, a horizontal cylinder fixed to said mounting base, a plunger rod shiftable in said cylinder and in engagement with the 50 graphophone brake lever during rotation of the graphophone turn-table, and means arranged within the path of swinging movement of the tone arm adapted for shifting the plunger rod to set the brake 55 lever.

2. An automatic stop device for graphophones comprising in combination with the graphophone tone arm and brake lever, a mounting base fixed to the graphophone 60 frame, a horizontal cylinder fixed to said mounting base, a plunger rod shiftable in said cylinder and in engagement with the graphophone brake lever during rotation of the graphophone turn-table, a post adjustably fixed to said mounting base, and means 65

supported on said post and arranged in the path of movement of said tone arm adapted to shift the plunger rod to effect the setting of the brake lever.

3. An automatic stop device for graphophones comprising in combination with the graphophone tone arm and brake lever, a mounting base fixed to the graphophone frame, a horizontal cylinder fixed to said mounting base, a plunger rod shiftable in 75 said cylinder and in engagement with the graphophone brake lever during rotation of the graphophone turn-table, a post adjustably fixed to said mounting base, a rod supported on said post and in engagement 80 with said plunger rod adapted to be engaged by the tone arm for shifting the plunger rod to effect the setting of the brake lever.

4. An automatic stop device for graphophones comprising in combination with the graphophone tone arm and brake lever, a mounting base fixed to the graphophone frame, a horizontal cylinder fixed to said mounting base, a plunger rod shiftable in 90 said cylinder and in engagement with the graphophone brake lever during rotation of the graphophone turn-table, a post adjustably fixed to said mounting base, a rod supported on said post and in engagement 95 with said plunger rod adapted to be engaged by the tone arm for shifting the plunger rod to effect the setting of the brake lever, and means for retaining the lower end of the rod operatively positioned 100 relative to said plunger rod.

5. An automatic stop device for graphophones comprising in combination with the graphophone tone arm and brake lever, a mounting base fixed to the graphophone 105 frame, a horizontal cylinder fixed to said mounting base, a plunger rod shiftable in said cylinder and in engagement with the graphophone brake lever during rotation of the graphophone turn-table, a post adjustably fixed to said mounting base, a rod supported on said post and in engagement 110 with said plunger rod adapted to be engaged by the tone arm for shifting the plunger rod to effect the setting of the brake lever, the inner end of said cylinder being slotted for the reception of said rod and a spring carried by said cylinder for maintaining the lower end of the rod within the cylinder slot.

6. An automatic stop device for graphophones comprising in combination with the graphophone tone arm and brake lever, a mounting base fixed to the graphophone frame, a horizontal cylinder fixed to said mounting base, a plunger rod shiftable in 125 said cylinder and in engagement with the graphophone brake lever during rotation of the graphophone turn-table, a post adjustably fixed to said mounting base, a rod 130

supported on said post and in engagement with said plunger rod adapted to be engaged by the tone arm for shifting the plunger rod to effect the setting of the 5 brake lever, and means for limiting the swinging movement of said rod.

7. An automatic stop device for graphophones comprising in combination with the graphophone tone arm and brake lever, a 10 mounting base fixed to the graphophone frame, a horizontal cylinder fixed to said mounting base, a plunger rod shiftable in said cylinder and in engagement with the graphophone brake lever during rotation 15 of the graphophone turn-table, a post ad-

justably fixed to said mounting base, a rod supported on said post and in engagement with said plunger rod adapted to be engaged by the tone arm for shifting the plunger rod to effect the setting of the brake 20 lever, and means adjustably mounted on said post for limiting the swinging movement of said rod.

Signed at Brooklyn in the county of Kings and State of New York, this 26 day 25 of March, A. D., 1920.
